UNITED STATES PATENT OFFICE.

JASPER H. STANFIELD, OF MUSKEGON, MICHIGAN.

GEARING FOR WASHING-MACHINES.

SPECIFICATION forming part of Letters Patent No. 707,949, dated August 26, 1902.

Application filed March 22, 1902. Serial No. 99,479. (No model.)

To all whom it may concern:

Be it known that I, JASPER H. STANFIELD, a citizen of the United States, residing at Muskegon, in the county of Muskegon and 5 State of Michigan, have invented a new and useful Driving-Gear for Washing-Machines, of which the following is a specification.

This invention relates generally to washing-machines, and more particularly to that 10 class known as "agitator" washing-machines, in which the agitating-rubber is intermittently rotated in opposite directions.

The object of the invention is to provide an 15 improved driving mechanism whereby the agitator is rapidly revolved by means of a steady and easy movement of the crank-wheel; and another object of the invention is to provide a driving mechanism which can be attached to the hinged lid, so that the entire 20 driving mechanism can be turned back whenever the lid is opened, and thereby avoid the necessity of removing one or more parts of the driving mechanism for the purpose of opening the lid.

25 With these objects in view the invention consists in the novel features of construction and arrangement of the various parts, all of which will be fully described hereinafter and pointed out in the claims.

30 In the drawings forming part of this specification, Figure 1 is a perspective view of a washing-machine provided with my improved construction of driving mechanism. Fig. 2 is a top plan view of the same. Fig. 3 is a 35 side elevation, partly in section, to illustrate the agitator within the tub. Fig. 4 is a detail sectional view illustrating the connection between the drive-shaft and reciprocating rack-bar.

40 Referring to the drawings, A represents a tub, which is preferably constructed of galvanized iron and corrugated and provided with suitable rack-sockets A', into which are fitted supporting-legs A''. A suitable top A³ is arranged in the tub, said top being provided with a hinged cover A⁴, to which the entire driving mechanism for operating the agitator B is attached. This agitator B comprises a shaft B', which projects upwardly 45 through the hinged cover and carries a pinion C. The lower end of the shaft has a disk B² connected therewith, from the lower face

of which project the rubbing or scrubbing pins B³. The pinion C intermeshes with a rack-segment D, which segment is connected 55 integrally with the casting E, having the hub portion E', through which a pivot-pin E² passes, said pivot-pin being connected to a plate F, fastened to the hinged cover and through which the shaft B passes, as most 60 clearly shown. The casting is also provided with rack-teeth E³ upon the opposite side of the pivot-pin, which rack-teeth intermesh with a rack-bar G, which reciprocates upon a rib F', formed integral with the plate 65 F, and the said plate is also formed with an upwardly-projecting lug F², through which the reduced circular end of the rack-bar passes, and between the rack-teeth and said reduced portion is a frame H', in which operates a roller I, mounted upon the end of the shaft K, said shaft being journaled in the brackets F³ and F⁴, integral with the plate F, said plate projecting to the edge of the top of the tub, as most clearly shown; but the said 70 plate is only connected to the hinged cover so that when the said cover is open all of the driving mechanism herein described will be carried back with the cover, and thereby avoid the necessity of removing any of the 75 operative parts for the purpose of opening the cover:

In practice I prefer to construct the reciprocating rack-bar with a depending rib H², which works in a groove F⁵, produced in the 85 rib F', thereby serving to guide the rack-bar, and consequently holding the same in its proper position during its various movements. An antifriction-roller L is also mounted upon the plate F just to one side of the rack-bar, 90 thereby aiding in holding the rack-teeth of the said bar in engagement with the rack-teeth of the casting E. I also prefer to provide the shaft I with a crank I', upon which is mounted the roller I.

95 It will thus be seen that I provide an exceedingly cheap and simple construction of driving mechanism for washing-machines by means of which a quick motion can be obtained by an easy revolution of the crank-handle M, and it will also be noted that the entire driving mechanism is mounted upon the hinged cover, so that the said cover can be opened at any time desired without remov-

ing or disconnecting any of the driving mechanism.

Having thus fully described my invention, what I claim as new, and desire to secure by 5 Letters Patent, is—

1. In a machine of the kind described, the combination with a base-plate, of a casting pivoted thereon, said casting having internal and external gear-teeth, a reciprocating rack-bar adapted to engage the external teeth, a pinion arranged for engagement with the internal teeth, and means for operating the reciprocating rack-bar, substantially as described.

15 2. The combination with a base-plate provided with a rib and guide-lug, of a casting pivoted thereon, said casting having interior

and exterior gear-teeth, a pinion arranged for engagement with the interior gear-teeth, a reciprocating bar adapted to slide upon the rib 20 formed upon the base-plate, and through the guide-lug connected to the said base-plate, said rack-bar and exterior gear-teeth intermeshing with each other, a drive-shaft mounted upon the base-plate, and having a crank-arm attached to its inner end, a roller pivotally connected to said crank-arm, a frame integral with the rack-bar and in which the roller operates, all arranged and adapted to operate substantially as described.

JASPER H. STANFIELD.
